UNITED STATES PATENT OFFICE.

JOHN COUNTER, OF CLEVELAND, OHIO.

WATCH-HOLDING CASE.

SPECIFICATION forming part of Letters Patent No. 734,403, dated July 21, 1903.

Application filed March 11, 1902. Serial No. 97,798. (No model.)

To all whom it may concern:

Be it known that I, JOHN COUNTER, a citizen of the United States, residing in Cleveland, county of Cuyahoga, in the State of Ohio, have invented a new and useful Watch-Holding Case, of which the following is a specification.

The objects of the invention are to provide a suitable case or support for a motorman's timepiece, which can be secured to the dashboard or stanchions of the car-vestibule, so that it is in position for instant reference at any moment, and its use will not interfere with the necessary time and attention required of the motorman while managing his controller and brake and the sharp lookout essential to the good management of a trolley-car.

A further object is to so mount the case that it will not be disturbed by the shock of starting or stopping the car or by the vibrations occasioned by the movements of the car when running at full speed, and, further, to protect the entire watch from dust or moisture, which would soon ruin it if it were left exposed thereto, and also to insulate it from extreme effects of the heat and cold.

I attain these objects by means of the device hereinafter described, shown in the accompanying drawings, and specifically pointed out in the claims.

In the accompanying drawings, Figure 1 is a face view or front elevation of the complete device. Fig. 2 is a side view of the same, the spring-clamp being removed. Fig. 3 is a side view of the spring-clamp. Fig. 4 is a vertical section of the hollow screw.

In the Figures, Y is the body of the case, shaped to conform to the shape of the watch and packed with felt or similar substance to prevent injury to its surface.

U is the head of the case, shaped to receive the stem and ring of the watch. These may be made integral or of more than one piece, if required.

W is the cover, which is provided with a glass front and screws upon the open front of the body Y. It is placed within the recess suitable to receive it.

50 In the head U of the case a hole is vertically drilled and threaded to receive the hollow screw S, through the reduced outer ex-

tremity of which passes the plunger-pin R, which is provided with a head r too large to pass out of the inlet-opening. A coiled 55 spring T encircles this pin and engages the head r and narrowed extremity of the inlet-opening in the screw. The plunger-pin is provided with a T-shaped head which is drilled to receive the bent portion of a pin or link H and swing freely thereon. A nut P secures the link in the plunger-head. The other extremity of the bent pin or link H passes through the clamp K and serves as a pivot for the jaws thereof, and a spring Z is 60 employed to close the jaws together. This spring and the spring T may be made of any desired shape or material. It will be seen that the link pivoting in the clamp permits it to swing freely in one plane, and the bent 65 portion of the link in the plunger-head M permits of free motion in a vertical plane, so that the clamp can be attached in any convenient place and still the case will hang vertically, so there will be little difficulty in 70 finding a place of attachment for the clamp. The spring about the plunger-head R takes up all vibration, so that no sudden jar will affect the watch within the case, and the narrowed walls of the hollow screw will prevent the plunger from coming out. A hole is 75 so made through the head of the case, in which the bent pin can be inserted if it is desired to dispense with the plunger.

It will readily be seen that this case affords 80 protection from weather and changes of temperature to every portion of the watch, and while it can be easily attached to stanchions, sills, or other projecting parts of a car it will swing freely when the car rocks and the 85 spring-actuated plunger will take up all the jar arising from the effects of uneven movements of the car upon rough track. A further advantage is found in the form of a clamp, which adapts it to be hung upon the motor-man's coat when changing cars and leaves 90 his hands free for other work.

I do not claim the exact shape of the springs or other portions of the device; but these may be modified considerably without departing 95 from the spirit of the invention.

Having described my invention, what I claim as new, and desire to secure by Letters Patent, is—

1. The combination with a case arranged to wholly inclose a watch and provided with a transparent cover, of a head therefor arranged to inclose the watch stem and ring, a bent pin pivoted thereto on which the case swings freely in one plane, a clamp comprising jaws through which the other extremity of the bent pin passes, and which forms the pivot therefor, and a spring adapted to close said jaws, substantially as described.
- 5 2. The combination with a case arranged to wholly inclose a watch and its stem, an extension of said case a hollow screw inserted therein provided with a reduced inlet-opening, a plunger-pin therein provided with a head, a spring within said screw engaging said head and the walls of the reduced opening, a T-head upon the exterior of the pin, a bent
- 10 15

portion of a pin pivoted therein, a clamp, the jaws of which are pivoted upon said link, and a spring adapted to close said jaws, substantially as described.

3. In combination with a case adapted to wholly inclose a watch, of means for attaching the same to a projecting portion of a car, comprising a clamp composed of spring-actuated jaws, and a bent link pivoted to said jaws and to said case, substantially as described.

In testimony whereof I have signed my name to this specification in the presence of two subscribing witnesses.

JOHN COUNTER.
